LIQUID TREATMENT OF YARNS

Robert Wighton Moncrieff, Frank Brentnall Hill, and Thomas Barnard Frearson, Spondon, near Derby, England, assignors to Celanese Corporation of America, a corporation of Delaware

Application January 18, 1935, Serial No. 2,324
In Great Britain February 8, 1934

8 Claims. (Cl. 8—154)

This invention relates to the liquid treatment of yarns, and has as its principal object to provide a means for carrying out effectively such treatment upon yarns wound into packages.

5 While the liquid treatment of yarn in package form presents many advantages, including the possibility of avoiding re-winding the yarn before and/or after the treatment, considerable difficulties are met with in practice in effecting uniform 10 treatment of the yarn, especially where the yarn is fine in character and where it consists of continuous filaments, and particularly if the filaments are only lightly twisted together.

We have now found that uniform treatment of 15 yarn on a bobbin can be effected by surrounding a bobbin with a casing and forcing treating liquor through the bobbin into the casing, the casing being maintained full during the operation and the liquor being allowed to escape from the casing 20 at a slow rate so that considerable pressure is maintained in the casing. The whole of the yarn on the bobbin is thus subjected to the liquor under pressure so that not only is the yarn uniformly treated along the length of the bobbin, but also 25 throughout the thickness of the bobbin, because the pressure maintained in the surrounding liquor by the casing precludes rapid flow through the outer layer of yarn.

The bobbin is suitably perforated or slotted so 30 as to provide for substantially uniform distribution of the liquor introduced under pressure within the hollow bobbin. A lining of gauze or the like may also be employed to assist in such distribution.

35 The requisite pressure is conveniently set up by means of centrifugal force. Thus, the bobbin may be mounted on a perforated or slotted spindle driven by any convenient means at the requisite speed. The liquor is then supplied to the interior 40 of the hollow spindle, centrifugal force driving the liquor through the yarn on the bobbin into the surrounding casing. When the casing becomes full, the liquor in it reaches considerable pressure.

A slow rate of flow of the liquor from the outer 45 casing is conveniently effected by the provision of fine perforations through which the liquor is flung by the rotation of the casing. These perforations are preferably symmetrically placed round the casing to avoid the setting up of vibrations, and have a size appropriate to the flow desired at the speed of operation employed. For example, for operation at speeds up to say 15,000 or 16,000 revolutions per minute, two or three 50 holes may be used of a diameter up to .015 inch.

55 Liquor is supplied to the hollow spindle at a

rate sufficient to make up for the flow from the casing and to keep the spindle filled over the length occupied by the bobbin.

By way of example one form of apparatus according to the invention will now be described in greater detail with reference to the accompanying drawing, in which

Fig. 1 is a diagrammatic elevation partly in section of the apparatus;

Fig. 2 shows in section a detail of the apparatus 10 of Fig. 1, and

Fig. 3 is a horizontal cross-section of the bobbin illustrated in Fig. 2.

Referring to Fig. 1, the apparatus comprises a rail 5 carrying a spindle mounting 6 which supports a spindle 7. The spindle 7 is inverted, the wharf 8 by means of which it is driven being at its upper end just below the rail 5.

As seen in Fig. 2, the spindle 7 is hollow, is closed at the bottom by means of a plug 9, and is provided with a number of perforations 10. A knurled nut 11 is provided on a threaded part 12 of the spindle 7, the nut 11 supporting a large flanged member 13 into which fits a wide sleeve or casing 14 which may conveniently be welded thereto. A further nut 15 on the threaded portion 12 supports a bobbin 16, a rubber ring 17 being interposed between the nut 15 and the bobbin 16. Towards the upper end of the spindle 7 there is fitted a further large flange 18 of the same size as the flange 13, into which the upper end of the casing 14 fits. The casing 14 and the upper flange 19 of the bobbin 16 are pressed by means of the nuts 11 and 15 against a rubber packing ring 20. Three small perforations 21 are provided in the casing 14, at points symmetrically disposed around it. The hollow spindle 7 is tapered internally, being narrower towards its upper end than at its lower end.

Referring again to Fig. 1, the entire spindle 40 assembly is surrounded by means of a guard casing 23 from the bottom of which a drain 24 leads into a drain tank 25. The upper end 26 of the spindle 7, which is open at the top is also surrounded by a guard 27 from which a drain 28 45 leads into the drain tank 25. The liquid with which the yarn is to be treated is supplied from a feed tank 30 through a feed pipe 31 and valve 32 to the open upper end 26 of the spindle 7. The liquid running into the drain tank 25 is conveyed by means of a pump 33 and pipes 34 back to the feed tank 30.

The spindle 7, together with the bobbin 16 mounted thereon and the flanges 13, 18 and the casing 14, is set in rotation by means of the wharf 55

8, and the liquid, with which the space inside the casing 14 is fed from the feed tank 30, is flung outwards under centrifugal force, issuing slowly from the fine orifices 21. The valve 32 is adjusted so that, after the space within the casing 14 has been entirely filled, the rate of supply of liquid from the feed tank 30 to the interior of the spindle 7 is sufficient to make up the amount of liquid issuing from the orifices 21. Any excess 10 of liquid fed by the pipe 31 is flung out by centrifugal force and caught by the guard 27 from which it drains to the tank 25. The liquid flung through the orifices 21 is caught by the guard 23 and runs through the drain 24 also into the drain 15 tank 25 from which the liquid is returned to the feed tank 30. By these means the liquid applied is forced through the yarn 35 wound on the bobbin 16, under high pressure, and at a rate which is slow by reason of the fineness of the orifices 21. 20 As a result, the yarn 35 is uniformly treated with the liquid throughout its entire thickness on the bobbin.

The rail 5 may conveniently serve as a support for a series of spindles, all the spindles being fed, if desired, by a common feed tank 30, and draining into a common drain tank 25. Uniformity of treatment of the several packages simultaneously treated in one batch, and of the several batches successively treated may be ensured by any convenient means, e. g. by ensuring that the same quantity of liquid flows through each package.

The employment of an inverted spindle 7 having a driving wharl 8 near the upper end thereof not only makes for steadier running, the greater part of the weight of the spindle being below the bearings which support it, but also prevents the wharl and the driving belt therefor from being splashed with the liquid issuing from the orifices 21. The tapered boring of the spindle 7 causes the liquid initially introduced at the upper end 26 of the spindle to be flung towards the bottom of the spindle and ensures that the system is filled with liquid.

45 The bobbin employed and illustrated in vertical section in Fig. 2 is shown in horizontal section in Fig. 3. The bobbin is made throughout of steel, and the barrel thereof on which the yarn 35 is wound consists of a number of bars 36 of 50 triangular cross-section between which are spaces 37 through which the liquid is thrown by centrifugal action. Outside the bars 36 is wound a cylinder of wire gauze 38 with which the yarn 35 is in direct contact. If desired, a similar cylinder 55 of wire gauze may be fitted inside the hollow spindle 7 in order that the liquid flowing out from the spindle may be more evenly distributed.

The speed of rotation of the spindle 7 varies in accordance with the nature of the yarn undergoing treatment and of the liquor itself, especially the viscosity of the liquor. Low-twisted continuous filament yarn requires a greater rate of rotation than yarn of higher twist, but uniform treatment can be effected even with low twist 65 continuous filament yarn substantially parallel wound on to the bobbin. Again, the finer the denier of the filaments in such yarn the greater the rate of rotation necessary. The liquor is supplied and the spindle 7 kept in rotation for a 70 period depending on the extent of treatment required.

As examples of liquid treatments which may be carried out by the method and means according to the invention may be mentioned, 75 washing, bleaching, and dyeing of yarns in gen-

eral, the invention being particularly suitable for the treatment of artificial continuous filament yarn, e. g. cellulose acetate or other cellulose derivative yarn, and viscose, nitrocellulose, and cuprammonium artificial silk. In the case of 5 dyeing, dyestuffs may be employed as solutions or dispersions, care being taken in the latter case to see that an adequate amount of dispersing agent is present. The invention may also be employed in connection with the complete or partial 10 saponification of cellulose acetate or other cellulose ester yarns, a suitable saponifying agent, together, if desired, with a small quantity of wetting agent being forced under pressure through the material. For example, a solution 15 of caustic soda of say 2%, 5%, 15% or higher concentration may be passed through a bobbin of cellulose acetate yarn until the cellulose acetate has reached the desired degree of saponification. 20

The invention may also be applied to the treatment of yarn wound in cake form, as produced by centrifugal boxes in wet processes for the production of artificial filaments. Thus, using the method of applying pressure described above with 25 reference to the drawing, the cake may be placed within a perforated shell and mounted on the spindle 7. The shell is surrounded by the casing 14 perforated to permit and control the flow of liquor supplied to the interior of the cake. 30 In order to distribute the liquor over the inner layers of the cake, a perforated shell similar to the wire gauze 38 may be placed inside the cake, liquor being supplied at a rate sufficient to cover the whole length of this inner shell. Apart from 35 washing, bleaching, and dyeing yarn in cake form, this application of the invention is advantageous in connection with saponifying or otherwise treating stretched cellulose acetate or other yarns which have been collected in centrifugal boxes at the end of the stretching operation. 40

What we claim and desire to secure by Letters Patent is:—

1. Process for the liquid treatment of yarn in 45 package form, which comprises feeding a treating liquid into a hollow yarn package and rapidly rotating said package so as to force said liquid through the yarn on said package by pressure due to centrifugal force, said package being 50 completely immersed in treating liquid contained in a casing from which said liquid is allowed to issue at a rate such that the liquid in the casing is maintained under super-atmospheric pressure.

2. Process for the liquid treatment of yarn in 55 package form, which comprises feeding a treating liquid into a hollow yarn package, rapidly rotating said package so as to force said liquid through the yarn on said package by pressure due to centrifugal force, said package being completely immersed in treating liquid contained in a casing from which said liquid is allowed to issue at a rate such that the liquid in the casing is maintained under a pressure substantially greater than that outside the casing. 60

3. Process for the saponification of yarn containing a cellulose ester while such yarn is in package form, which comprises feeding a saponifying liquid into a hollow package of yarn comprising cellulose ester filaments and rapidly 70 rotating said package so as to force said liquid through the yarn on said package by pressure due to centrifugal force, said package being completely immersed in treating liquid contained in a casing from which said liquid is allowed to 75

issue at a rate such that the liquid in the casing is maintained under a pressure substantially greater than atmospheric.

4. Process for the dyeing of yarn in package form, which comprises feeding a dye liquor into a hollow yarn package and rapidly rotating said package so as to force said liquor through the yarn on said package by pressure due to centrifugal force, said package being completely immersed in treating liquid contained in a casing from which said liquid is allowed to issue at a rate such that the liquid in the casing is maintained under a pressure substantially greater than atmospheric.

5. Apparatus for the liquid treatment of yarn in package form, comprising a casing provided with an outlet means, means for holding a hollow yarn package coaxially in said casing, means for feeding treating liquid to the interior of said package, and means for rapidly rotating said casing with the yarn package contained therein, so as to force the liquid fed into the package through the yarn on the package under pressure and out through said outlet means, said outlet means being of such dimensions as to offer a substantial resistance to the liquid flow.

6. Apparatus for the liquid treatment of yarn in package form, comprising a casing provided with an outlet means having a cross-sectional area not exceeding the order of 6×10^{-4} square centimeters, means for holding a hollow yarn package coaxially in said casing, means for feeding treating liquid to the interior of said package, means for rapidly rotating said casing with the yarn package contained therein, so as to force the liquid fed into the package through the yarn on the package under pressure and out through said outlet means, and means sur-

rounding the casing and adapted to catch the liquid flowing therefrom.

7. Apparatus for the liquid treatment of yarn in package form, comprising a casing provided with an outlet means, means comprising a perforated hollow spindle adapted to carry a hollow yarn package coaxially in said casing, driving means for said spindle at the upper end thereof, means for feeding treating liquid to the interior of said package, and means for rapidly rotating said casing with the yarn package contained therein, so as to force the liquid fed into the package through the yarn on the package under pressure and out through said outlet means, said outlet means being of such dimensions as to offer a substantial resistance to the liquid flow.

8. Apparatus for the liquid treatment of yarn in package form, comprising a perforated hollow spindle, means at the upper end of said spindle for rapidly rotating the same, a flange on said spindle near said driving means, a nut near the lower end of said spindle adapted to force a yarn package mounted on said spindle towards said flange, a cylindrical casing adapted to surround said flange and to fit into said flange, a further flange adapted to support said casing from beneath, a nut adapted to screw on to said spindle and to hold said further flange in position, means for feeding treating liquid to the interior of said spindle, said cylindrical casing being provided with at least one fine perforation such as to allow the liquid to escape but to offer a substantial resistance to its flow.
